TREE SUPPORT

Hiram M. Maxwell, 1748 N. Verdugo Road,
Apt. 7, Glendale, Calif. 91206

Filed Sept. 18, 1967, Ser. No. 8,626

Term of patent 14 years

(Cl. D35—1)

FIGURE 1 is a perspective view of a tree support embodying my new design, with a dotted line representation of a tree for illustrative purposes;

I claim:

The ornamental design for a tree support, substantially as shown and described.
